SAFETY SYSTEM FOR GAS BURNERS

Johannes Frege, Hasslinghausen Ueber, and Kurt Sachse, Gevelsberg, Westphalia, Germany, assignors to W. Krefft Aktiengesellschaft, Gevelsberg, Westphalia, Germany

Filed Jan. 20, 1959, Ser. No. 788,005

6 Claims. (Cl. 158—125)

This invention relates to safety systems for gas burners, and lends itself to gas heating systems of any kind, particularly gas ranges.

It is a general object of this invention to improve prior art safety systems for gas ranges.

This invention is concerned with gas heating systems which are free from the dangers normally resulting from a temporary reduction of gas pressure, or a temporary interruption of the supply of gas, and the object of the present invention is to achieve this end with simpler and more effective means than in prior art gas ranges.

When a pilot burner fails to ignite a main burner, and gas is allowed to escape under such conditions through the main burner, the gas forms a highly explosive and generally toxic mixture with ambient air. Such mixtures tend to endanger life due to the toxicity thereof, and may cause great damage when accidentally ignited.

It is another object of this invention to provide gas heating systems having semi-automatic controls positively precluding the unintentional escape of gas from non-ignited gas burners, and thus precluding formation of dangerously toxic and/or explosive mixtures of gas and air.

Still another object of the invention is to provide gas heating systems wherein the main burner is provided with a pilot burner for igniting the main burner and with means responsive to the radiation emitted from the pilot burner which means, in turn, control interlocks adapted to assure safe operation of the heating system.

Still another object of the invention is to provide means for accelerating certain change-over switching operations which are necessary to achieve the aforementioned ends.

Further objects and advantages of the invention will become apparent as the following description proceeds, and the features of novelty which characterize the invention will be pointed out with particularity in the claims annexed to, and forming part of, this specification.

For a better understanding of the invention reference may be had to the accompanying drawings wherein

FIG. 1 is a diagrammatic representation of a gas range embodying the invention;

FIG. 1a is a diagrammatic representation of a modified version of the range shown in FIG. 1.

Referring now to FIG. 1, numeral 2 has been applied to generally indicate a transformer having three secondary windings 2', 2'', 2''''. The primary circuit, or supply circuit, of transformer 2 includes fuse 1' and switching device 1. Winding 2' feed by means of leads 109, 110 the filament 3' of thyatron 3. Winding 2''' is connected to a rectifier 5 made up of two rectifier cells. The D.C. output circuit of rectifier 5 energizes solenoid valves 12, 14 and 15 when the winding of relay or change-over relay 6' is energized. Relay 6' comprises a pair of movable contacts 6a, 6b. Contact 6a is adapted to cooperate with a pair of fixed contacts 6a' of which the right contact is a blind contact, i.e. a contact not connected to any circuit terminal. Contact 6b is adapted to cooperate with a pair of fixed contacts 6b' of which the left is a blind contact. When the winding of relay 6' is energized the two contacts 6a, 6b controlled by relay 6' are in the right position thereof and the load circuit of rectifier 5 runs as follows: Center tap 100 between the two rectifier cells 5; movable contact 6b; right

2

fixed contact 6b'; lead a, relay 17 and solenoid valves 12, 14 and 15 in parallel; lead b; and center tap of transformer winding 2''''. When relay 6' is not energized the movable contacts 6a, 6b controlled by relay 6' are in the left position thereof and then transformer winding 2''' applies an A.C. voltage to three serially connected igniters 7 of the incandescent type of which each is associated with one of three pilot burners 7'. The circuit of igniters 7 when closed runs as follows: Upper terminal of winding 2''''; lead c; movable contact 6a'; left fixed contact 6a'; all three igniters 7 in series; lead d; lower end of secondary winding 2''''. The three pilot burners 7' are supplied with gas by line T branching off manifold M to which cooking burners or main burners B are connected by the intermediary of solenoid valves 12, 14, 15. Transformer winding 2'' is connected to a rectifier bridge circuit 4 whose D.C. output circuit includes leads 111 and 112 and two resistors 9, 10 forming a potentiometer. Resistors 9, 10 are shunted by a capacitor 22 for decreasing ripples in the output of rectifier 5. The grid bias of tube 3 is taken from potentiometer 9, 10. The grid circuit of tube 3 includes serially connected resistors 8 having a negative temperature coefficient of resistance and also includes resistors 19, 20 and 21. Each of resistors 8 is arranged immediately adjacent one of pilot burners 7' and exposed to the heat radiated therefrom. Resistors 8 are connected by lead e to the point of potentiometer 9, 10 between resistors 9 and 10 and resistors 19, 20 and 21 are connected by lead f to the negative terminal of potentiometer 9, 10. Resistors 19 and 20 are adjustable making it possible to negatively bias the control grid 3''' of thyatron 3, thus precluding any flow of plate current. Resistor 21 arranged immediately adjacent to the control grid 3''' of thyatron 3 is a grid limiting resistor provided for grid protection. Grid 3'' of thyatron 3 is conductively connected to the cathode 3' thereof. Manifold M comprises a manually operable cock R for admitting gas to cooking or main burners B and pilot burners 7'. This cock which is arranged at a point upstream from the point where line T branches off manifold M is mechanically coupled with switch 1 in the primary circuit of transformer 2 in such a way that when gas is being admitted to pilot burners 7' by opening that valve, the primary or energizing circuit of transformer 2 is being closed simultaneously by closing switch 1. As a result of energizing transformer 2 igniters 7 become immediately incandescent and ignite the combustible gas escaping at the pilot burners 7'. The heat generated at pilot burners 7' is transferred to resistors 8, as the result of which their resistance instantly decreases. This, in turn, reduces the negative grid bias of tube 3, causing the flow of a current in the plate circuit. This circuit includes plate or anode 3'', lead g and resistor 11 in addition to the aforementioned relay 6' and leads 103 and 102. The latter and lead 104 are connected to the terminals of transformer winding 2''. Resistor 18 shunts relay 6' when contact 17' under the control of relay 17 is in the left position thereof. The shunt across relay 6' includes lead h, movable contact 17', resistor 18 and lead j.

The operation of the arrangement of FIG. 1 is as follows:

Because of the mechanical coupling of the aforementioned cock R for admitting gas to manifold M and line T with switch 1, transformer 2 is always energized concomitant with admission of gas to the system. Upon admittance of gas to the system the gas escaping from pilot burners 7' is ignited by igniters 7. The heat radiated from pilot burners 7' results in a decrease of the resistance of resistors 8 directly included in the circuit of control grid 3''' of tube 3. This swings the bias of grid 3''' from negative to positive and initiates the flow

of plate current. The latter energizes relay 6', causing its two change-over contacts 6a, 6b to shift from their left position to their right position. This causes opening of the circuit of igniters 7 and closing of the circuit of solenoid valves 12, 14, 15 and opening of the latter and energizing of relay 17. The gas escaping at main burners B upon opening of solenoid valves 12, 14, 15 is ignited by pilot burners 7'. Energization of relay 17 causes movement of contact 17' from its right position to its left position, thus shunting resistor 18 across relay 6'.

Relay 6', i.e. the operating winding thereof, is energized by the maximum plate current which thyratron 3 is capable of supplying, and thus contacts 6a, 6b are rapidly moved against their bias from their left position shown in FIG. 1 to their right position. A smaller magnetic action is required to maintain contacts 6a, 6b in their right position than to rapidly move the same to their right position. Hence relay winding 6' may be de-energized to some extent after contacts 6a, 6b have completed their travel to their right position. This accelerates their movement to their left position as a result of a renewal of a cut-off of thyratron 3 and cessation of the flow of its plate current.

The flames at burners B may be turned off in different ways. All burners B may be turned off by closing the aforementioned cock R in manifold M, simultaneously de-energizing transformer 2. Then the entire system, including all its electrical components, is inoperative. As long as pilot burners 7' burn, the flame on any burner B will be re-ignited when the respective burner is being resupplied with gas. As soon as one or more of pilot burners 7' are extinguished, the temperature of one or more resistors 8 decreases and, therefore, the bias of control grid 3''' tends to become negative, to interrupt the flow of plate current and deenergize relay 6', causing both contacts 6a, 6b to move from their right positions to their left positions illustrated in FIG. 1. This causes interruption of the circuits of solenoid valves 12, 14, 15 and closing of these valves, and it also causes closing of the circuit of igniters 7 and the igniters to become incandescent. Shunting of relay 6' by contact 17' and resistor 18 accelerates the change-over operation of relay 6' when the bias of grid 3''' swings from positive to negative since it diverts a portion of the plate current of tube 3 from relay 6'.

The arrangement of parts of FIG. 1a is substantially the same as that shown in FIG. 1 and the same reference characters have been applied in FIGS. 1 and 1a to indicate like parts. Hence the arrangement of FIG. 1a calls only for an additional description inasmuch as it deviates from that shown in FIG. 1.

FIG. 1a illustrates another shunt arrangement causing a portion of the plate current of tube 3 to by-pass relay 6'. The arrangement shown in FIG. 1a may, if desired, take the place of parts 17, 17', 18 of FIG. 1. According to FIG. 1a relay 6' is shunted by two variable resistors 18', 18''. The latter has a high negative temperature coefficient of resistance. The plate current of tube 3 flows in parallel paths through relay 6' and resistors 18' and 18''. Resistor 18'' is heated by $i^2 \cdot r$ losses as a result of the flow of current through it, causing its resistance to decrease and to carry a progressively increasing portion of the total plate current of tube 3. In other words, relay 6' is being progressively deenergized by resistor 18'', thus accelerating the change-over of contacts 6a, 6b from their right positions to their left positions on cooling of resistors 8.

Interruption of the gas service causes simultaneous extinction of the main burners B and of the pilot burners 7'. Therefore resistors 8 cool down, their resistance increases, the bias of grid 3''' swings from positive to negative and interrupts the flow of plate current through discharge tube 3. This deenergizes relay 6' causing contacts 6a, 6b to move from right to left and to close the circuit of igniters 7.

Therefore pilot burners 7' will be ignited whenever service is restored and gas escapes at the nozzle of pilot burners 7'.

The same sequence of steps occurs whenever one of the main burners should be extinguished by a draft. It is possible to manufacture resistors having a negative temperature coefficient of resistance and changing their resistance drastically at the occurrence of relatively small changes in temperature in sub-miniature size.

It will be observed that the circuitry of FIGS. 1 and 1a involves three separate and distinct stages: (1) The grid circuit of thyratron 3 including sensing resistors 8; (2) the energizing circuit of relay 6' which is identical with the plate circuit of thyratron 3; and (3) the circuits of solenoid valves 12, 14, 15 and electric igniters 7. As mentioned, these three stages are separate and in the above sequence each of the three stages is adapted to carry increasingly larger currents and each stage involves an increasingly larger power.

The combination of a temperature sensing element in the form of a resistor having a negative temperature coefficient of resistance with a thyratron yields an extremely critical or sensitive on-off characteristic which could neither be achieved by combining a temperature sensing element in the form of a resistor having a positive temperature coefficient of resistance with a thyratron or by combining a temperature-sensing element in the form of a resistor having a negative coefficient of resistance with a grid-controlled high vacuum electron tube.

Since the thyratron 3 carries either its full plate current or no plate current at all, relay 6' will either be fully energized, or de-energized, depending upon the condition the thyratron 3 is in. In other words, the operation of contacts 6a, 6b of relay 6' is positive and is not affected by mechanical properties such as inaccuracies of relay 6'.

The coaction between temperature sensing elements in form of resistors 8 having a negative temperature coefficient of resistance with a thyratron is a pre-requisite for providing a series arrangement of such sensing resistors 8 of which each is associated with a pilot burner 7' and each controls the operation of relay 6' and that of its movable contacts 6a, 6b. A change in the resistance of each of resistors 8 is but a relatively small change in the aggregate resistance of all resistors 8, and if the change of the resistance of one single resistor 8 due to a relatively small change in temperature would not suffice to swing the bias of thyratron 3 so as to fully open or fully close the same, the above series connection of all sensing resistors 8 would be impossible.

It will also be understood that we have illustrated and described herein two preferred embodiments of our invention and that various alterations may be made in the details thereof without departing from the spirit and scope of our invention as defined in the appended claims.

We claim:

1. A gas distribution system comprising in combination:
  - (a) a manifold;
  - (b) a main gas burner supplied with gas from said manifold;
  - (c) an electromagnetic valve having a de-energized closed position and an energized open position admitting gas from said manifold to said main burner;
  - (d) a pilot burner supplied with gas from said manifold and operatively related to said main burner;
  - (e) an electric igniter operatively related to said pilot burner;
  - (f) an electromagnetic change-over relay for controlling said valve and said igniter and including an operating winding, said relay having a first position upon de-energization of said operating winding adapted to cause de-energization of said valve and energization of said igniter and said relay having a second position upon energization of said operating

- winding adapted to cause energization of said valve and de-energization of said igniter;
- (g) a thyratron having a plate circuit including said operating winding and a grid circuit including a control grid;
- (h) means for biasing said grid sufficiently negatively to inhibit the flow of current in said plate circuit as long as the resistance in said grid circuit exceeds a predetermined value;
- (i) a temperature sensing resistor having a negative temperature coefficient of resistance exposed to heat radiation emitted from said pilot burner arranged in said grid circuit; and
- (j) means for accelerating the switching operation of said relay from said second position thereof to said first position thereof, said accelerating means including normally ineffective shunt means across said operating winding of said relay adapted to become effective only upon completion of the movement of said relay from said first position thereof to said second position thereof.

2. A gas distribution system comprising in combination:

- (a) a manifold;
- (b) a main gas burner supplied with gas from said manifold;
- (c) an electromagnetic valve having a de-energized closed position and an energized open position admitting gas from said manifold to said main burner;
- (d) a pilot burner supplied with gas from said manifold and operatively related to said main burner;
- (e) an electric igniter operatively related to said pilot burner;
- (f) an electromagnetic change-over relay for controlling said valve and said igniter and including an operating winding, said relay having a first position upon de-energization of said operating winding adapted to cause de-energization of said valve and energization of said igniter and said relay having a second position upon energization of said operating winding adapted to cause energization of said valve and de-energization of said igniter;
- (g) a thyratron having a plate circuit including said operating winding and a grid circuit including a control grid;
- (h) means for biasing said grid sufficiently negatively to inhibit the flow of current in said plate circuit as long as the resistance in said grid circuit exceeds a predetermined value;
- (i) a temperature sensing resistor having a negative temperature coefficient of resistance exposed to heat radiation emitted from said pilot burner arranged in said grid circuit; and
- (j) means for accelerating the switching operation of said relay from said second position thereof to said first position thereof, said accelerating means including an additional electromagnetic relay adapted to be energized in response to completion of the movement of said first mentioned relay from said first position thereof to said second position thereof; and
- (k) said accelerating means further including means for shunting said operating winding in response to energization of said additional relay.

3. A gas distribution system comprising in combination:

- (a) a manifold;
- (b) a main gas burner supplied with gas from said manifold;
- (c) an electromagnetic valve having a de-energized closed position and an energized open position admitting gas from said manifold to said burner;
- (d) a pilot burner supplied with gas from said manifold and operatively related to said main burner;

- (e) an electric igniter operatively related to said pilot burner;
- (f) an electromagnetic change-over relay for controlling said valve and said igniter and including an operating winding, said relay having a first position upon de-energization of said operating winding adapted to cause de-energization of said valve and energization of said igniter and said relay having a second position upon energization of said operating winding adapted to cause energization of said valve and de-energization of said igniter;
- (g) a thyratron having a plate circuit including said operating winding and a grid circuit including a control grid;
- (h) means for biasing said grid sufficiently negatively to inhibit the flow of current in said plate circuit as long as the resistance in said grid circuit exceeds a predetermined value;
- (i) a temperature sensing resistor having a negative temperature coefficient of resistance exposed to heat radiation emitted from said pilot burner arranged in said grid circuit; and
- (j) means for accelerating the switching operation of said relay from said second position thereof to said first position thereof, said accelerating means including means establishing a shunt across said operating winding of said relay, said shunt-establishing means including a resistor having a negative temperature coefficient of resistance.
4. A gas distribution system comprising in combination:
- (a) a manifold;
- (b) a plurality of main gas burners connected in parallel and supplied with gas from said manifold;
- (c) a plurality of electromagnetically operated valves each arranged between said manifold and one of said plurality of main burners and each having a closed position and an open position admitting gas from said manifold to said one of said plurality of main burners;
- (d) a plurality of pilot burners supplied with gas from said manifold each operatively related to one of said plurality of main burners;
- (e) a plurality of electric igniters serially connected into an igniter circuit and each operatively related to one of said plurality of pilot burners;
- (f) an electromagnetic change-over relay for controlling said plurality of valves and said plurality of igniters and including an operating winding, said relay having a first position upon de-energization of said operating winding adapted to cause closing of said plurality of valves and energization of said plurality of igniters and said relay having a second position upon energization of said operating winding adapted to cause opening of said plurality of valves and de-energization of said plurality of igniters;
- (g) a thyratron having a plate circuit including said operating winding and having a grid circuit including a control grid;
- (h) means for sufficiently negatively biasing said control grid to inhibit the flow of current in said plate circuit as long as the resistance of said grid circuit exceeds a predetermined value;
- (i) a plurality of temperature sensing resistors having a negative temperature coefficient of resistance serially connected in said grid circuit each exposed to heat radiation emitted from one of said plurality of pilot burners and each adapted to inhibit the flow of current in said plate circuit and energization of said operating winding upon extinction of but one of said plurality of pilot burners and concomitant increase of said resistance of said grid circuit; and
- (j) means for accelerating the switching operation of said relay from said second position thereof to said first position thereof, said accelerating means in-

allel and jointly supplied with gas from said manifold.

- (c) a plurality of electromagnetically operated valves each arranged between said manifold and one of said plurality of main burners and each having a closed position and an open position admitting gas from said manifold to said one of said plurality of main burners;
- (d) a plurality of pilot burners jointly supplied with gas from said manifold each operatively related to one of said plurality of main burners;
- (e) a plurality of electric igniters serially connected into an igniter circuit and each operatively related to one of said plurality of pilot burners;
- (f) an electromagnetic change-over relay for controlling said plurality of valves and said plurality of igniters and including an operating winding, said relay having a first position upon de-energization of said operating winding adapted to cause closing of said plurality of valves and energization of said plurality of igniters and said relay having a second position upon energization of said operating winding adapted to cause opening of said plurality of valves and de-energization of said plurality of igniters;
- (g) a thyratron having a plate circuit including said operating winding and having a grid circuit including a control grid;
- (h) means for biasing said control grid sufficiently negatively to inhibit the flow of current in said plate circuit as long as the resistance of said grid circuit exceeds a predetermined value;
- (i) a plurality of temperature sensing resistors having a negative temperature coefficient of resistance serially connected in said grid circuit each exposed to heat radiation emitted from one of said plurality of pilot burners and each adapted to inhibit a flow of current in said plate circuit and energization of said operating winding upon extinction of but one of said plurality of pilot burners and concomitant increase of said resistance of said grid circuit; and
- (j) means for accelerating the switching operation of said relay from said second position thereof to said first position thereof, said accelerating means including an additional electromagnetic relay adapted to be energized in response to completion of the movement of said first mentioned relay from said first position thereof to said second position thereof, said accelerating means further including means for shunting said operating winding of said relay in response to energization of said additional relay.

5. A gas distribution system comprising in combination:

- (a) a manifold;
- (b) a plurality of main gas burners connected in parallel and jointly supplied with gas from said manifold;
- (c) a plurality of electromagnetically operated valves each arranged between said manifold and one of said plurality of main burners and each having a closed position and an open position admitting gas from said manifold to said one of said plurality of main burners;
- (d) a plurality of pilot burners jointly supplied with gas from said manifold each operatively related to one of said plurality of main burners;
- (e) a plurality of electric igniters serially connected into an igniter circuit and each operatively related to one of said plurality of pilot burners;
- (f) an electromagnetic change-over relay for controlling said plurality of valves and said plurality of igniters and including an operating winding, said relay having a first position upon de-energization of said operating winding adapted to cause closing of said plurality of valves and energization of said plurality of igniters and said relay having a second position upon energization of said operating winding adapted to cause opening of said plurality of valves and de-energization of said plurality of igniters;
- (g) a thyratron having a plate circuit including said operating winding and having a grid circuit including a control grid;
- (h) means for biasing said control grid sufficiently negatively to inhibit the flow of current in said plate circuit as long as the resistance of said grid circuit exceeds a predetermined value;
- (i) a plurality of temperature sensing resistors having a negative temperature coefficient of resistance serially connected in said grid circuit each exposed to heat radiation emitted from one of said plurality of pilot burners and each adapted to inhibit a flow of current in said plate circuit and energization of said operating winding upon extinction of but one of said plurality of pilot burners and concomitant increase of said resistance of said grid circuit; and
- (j) means for accelerating the switching operation of said relay from said second position thereof to said first position thereof, said accelerating means including means establishing a shunt across said operating winding of said relay, said shunt-establishing-means including a resistor having a negative coefficient of temperature.
